(57) **CLAIM**

The ornamental design for a removable liquid dispenser for bottle neck, as shown and described.

DESCRIPTION

FIG. 1 is a perspective view of a removable liquid dispenser for bottle neck, showing our new design in a position of use with the neck of an exemplary bottle;

FIG. 2 is a right side elevational view thereof;

FIG. 3 is a top plan view thereof;

FIG. 4 is a left side elevational view thereof;

FIG. 5 is a front elevational view thereof;

FIG. 6 is a rear elevational view thereof; and,

FIG. 7 is a bottom plan view thereof, shown independent of the exemplary bottle, to show aspects of the design not visible when combined.

The broken lines are shown for the purpose of illustrating environmental subject matter of an exemplary bottle and form no part of the claimed design.
